[57] CLAIM

The ornamental design for a stand mixer, as shown and described.

DESCRIPTION

FIG. 1 is a perspective view as seen from the top, front and left side of a stand mixer showing our new design;

FIG. 2 is a top plan view thereof; the bottom plan view is flat and unornamented;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a bottom plan view partially in section taken along line 7—7 in FIG. 4, it being understood that the interior structure of the stand mixer has been omitted and forms no part of the claimed design;

FIG. 8 is a perspective view as seen from the top, front and left side of a second embodiment of a stand mixer showing our new design;

FIG. 9 is a top plan view thereof; the bottom plan view is flat and unornamented;

FIG. 10 is a left side elevational view thereof;

FIG. 11 is a right side elevational view thereof;

FIG. 12 is a bottom plan view partially in section taken along line 12—12 in FIG. 11, it being understood that the interior structure of the stand mixer has been omitted and forms no part of the claimed design;

FIG. 13 is a front elevational view thereof; and,

FIG. 14 is a rear elevational view thereof.

The broken lines showing in FIGS. 1 and 8 of a bowl platform, power cord, and beaters are used for illustrative purposes only and form no part of the claimed design.
